UNITED STATES PATENT OFFICE.

ZEROY P. HOTCHKISS, OF OAK PARK, ILLINOIS, ASSIGNOR OF ONE-FOURTH
TO CARLOS J. WARD, OF SAME PLACE.

PRINTING TELEGRAPHY.

SPECIFICATION forming part of Letters Patent No. 403,472, dated May 14, 1889.

Application filed February 11, 1888. Serial No. 263,699. (No model.)

To all whom it may concern:

Be it known that I, ZEROY P. HOTCHKISS, a citizen of the United States, residing at Oak Park, in the county of Cook and State of Illinois, have invented a certain new and useful Improvement in Telegraphic Printing - Machines, which is fully set forth in the following specification, reference being had to the accompanying drawings, in which—

10 Figure 1 is a descriptive figure of the electric mechanism for operating my improved telegraphic printing-machine. Fig. 2 is a side elevation of my telegraphic printing-machine embodying my invention. Fig. 3 is a cross-section of the same, taken on the line 1 1 of Fig. 2. Fig. 4 is a similar view taken on the line 2 2 of Fig. 2. Fig. 5 is a detail section taken on the line 3 3 of Fig. 4, showing portions of the operating mechanism. Fig. 6 is a plan section taken on the line 4 4 of Fig. 2. Fig. 7 is a detail section of a portion of the ratchet-wheel 30, showing pin 105. Fig. 8 is a detail plan view of the shifting device at the right-hand end of the printing-machine. Fig. 9 is a cross-section of the same.

15 Like numbers refer to like parts in all the drawings.

My invention relates to the printing in full of all the words, figures, and characters of a telegram while the same is being received through the instrument at the station to which the telegram is sent. It has for its objects to print telegrams plainly, after the manner of the type-writers now in use, to do this from the sender's station, and to do it immediately—that is, to receive and print a telegram at the same time, turning it out of the machine ready for delivery. It has for another object economy. Skilled operators 40 may be dispensed with for receiving telegrams, since in using my machine nothing is to be done at the receiving-station except insert in the machine the paper on which the message is to be printed and remove it therefrom after the printing is done.

I will now proceed to describe in detail the construction and operation of the mechanism whereby my invention is carried into effect, and will then set forth what I claim as novel therein.

Referring again to the drawings, 1 represents the main-line wire; 2, the main-line binding-posts; 4, the coils of a main-line neutral relay supported by the post 3, which is

screwed to the base 5 of the relay and to the 55 connecting-bar of the coils.

14 is an armature pivoted at 27; 17, an insulated adjustable set-screw passing through the adjustment-post 40.

62 is a screw also passing through the adjustment-post 40 and insulated at its point.

15 is an adjustment-spring attached to armature 14 and to a branch of the post 40.

56 is the permanent magnet of a polarized main-line relay, to which the polarized armature 55 is pivoted at 57.

57½ is a set-screw to hold the negative coil 8 and the positive coil 10 in position.

58 is an adjustable insulated set-screw passing through the post 58½. 59 is a like screw 70 passing through the same post.

18 represents the wire of the local circuit and its connections. It starts at set-screw 17, and by wire 18 passes through the coils of the local magnets 19, then by wire 18 to the insulated set-screw 58, and (as the polarized armature 55 during this operation is in contact with set-screw 58) the current then passes through the pivot-screw 57, and by wire 61 to the local battery 23, and then by wire 18 into 80 the binding-post 25, and terminates in the armature 14.

41 represents connected wires, which start from the screw in the adjustment-post 42½, which is insulated from post 40, and terminate at the pivot-point of the governing-lever escapement 39, passing successively through the coils 42 of the local magnets and the local battery 47. 41 has a branch wire, 60, terminating at set-screw 59. The lever 39 is provided with platinum points 63 at its extreme end, which are screwed in it at right angles for the purpose of contact with like points at the ends of screws passing through the posts 42½ and 64.

67 represents a local wire passing from the screw of the adjustment-post 64, insulated from 40 at 66, to and through the local magnets 68, the metallic connection 67½ into the wire 41, and so on to and through the local battery 47 back to the pivot-point of the governing-escapement 39.

61 is a wire leading from the local battery 23 to the pivot-screw 57 of armature 55.

76 is a horizontal frame designed to support 105 the local mechanism. This is bent around the wheels 30 and 30½. 125 125 are upright standards screwed to this frame. 127 is the

main shaft rigidly attached to these standards.

30 is a ratchet-wheel with forty-eight teeth at equal distances upon its periphery. This wheel is secured to the type-bearing wheel 30 $\frac{1}{2}$. Upon the outer edge of the latter wheel are attached forty-six flat springs, 128, to the free end of which are attached the forty-six type-printing characters 129, (shown hereinafter,) and each character occupies a space

10 equal to that of a tooth on the wheel 30. Corresponding to the other two teeth of the forty-eight teeth on wheel 30 (which two teeth are ninety degrees apart) are two blank spaces on wheel 30 $\frac{1}{2}$.

15 87 105 113 are pins or studs projecting from the side of the ratchet-wheel 30.

35 is a spring-pawl pivoted to the wheel 30.

86 is a flat coiled spring, one end of which is attached to the main shaft 127 and the

20 other end to the wheel 30 $\frac{1}{2}$ by the screw 130.

90 is a ring ratchet-wheel secured to wheel 30 $\frac{1}{2}$ by screws passing through the slotted lugs 158. This wheel 90 has upon its opposite side a pin, 93, which passes through the slot 92 in

25 the wheels 30 and 30 $\frac{1}{2}$.

32 is a ratchet-wheel with eight teeth in its outer edge equal distances apart. Secured to this ratchet-wheel is a smaller ratchet-wheel, 32 $\frac{1}{2}$, with teeth corresponding to those of wheel 32. In the side of this smaller ratchet-wheel are four pins, 53, in a circle and equal distances apart.

85 is a longer pin or stud attached to the ratchet-wheel 32 $\frac{1}{2}$, and to which is attached 35 one end of a light flat coiled spring, 83, the other end of this spring being attached to the main shaft 127.

84 is a rigid arm attached to the frame 76, and at its upper end bent in hook form to en-

40 gage with the pin 85.

33 is a spring-pawl pivoted to a post, 131, which is rigidly attached to a lug, 132, of the frame 76.

19 19 are coils of local magnets, of well-known construction, attached rigidly to the frame 75. To cross-bars on this frame, at 133, is pivoted, by the adjustable set-screws 134, the armature 28, of usual construction.

137 137 are adjustable set-screws attached 50 to the frame 75, to regulate the distance which the armature 28 can move. The spring-pawls 29 and 31 are attached to armature 28 by any well-known device.

42 42 are coils of local magnets of the same 55 resistance in ohms as are those of 19 19, and are of well-known construction. They are supported by the frame 75. 49 is the armature of these coils bent and pivoted to the frame 75 by the set-screws 158 $\frac{1}{2}$.

60 139 is an adjustable set-screw passing through the armature 49.

140 is a part of the frame 75, through which the set-screw 141 passes, which regulates the distance that the armature 49 can move.

65 50 is a lever pivoted to the lug 132 of the frame 75. Pivoted to this lever at a right angle is the spring-pawl 51. Attached to the

opposite end of this lever is a retracting-spring 52, secured to the frame 75.

68 68 are the coils of local magnets of the same electrical resistance as those previously described. They are supported by the frame 75. 73 is the armature of these coils, and is pivoted to the frame 75 by the set-screw 74.

144 is an adjustable set-screw passing 75 through the armature 73.

145 is a portion of the frame 75, through which the adjustable set-screw 146 passes.

143 is a retracting-spring attached to the armature 73 and to the adjustable set-screw 80 147, which passes through a portion of the frame 75.

102 is a stop-arm slotted at one end, where it is pivoted to the frame 75 by the pin 148.

114 is a lug attached to and projecting below the stop-arm 102, and 142 is a similar lug projecting above the stop-arm 102 for the purpose of acting against the retracting-spring 150. At the front end of the stop-arm 102 is pivoted an upright arm, 107, curved 90 around the ratchet-wheel 32, and at its upper end bent at a right angle to the same plane as the stop-arm 102.

108 is a short projection at a right angle on the upper bent end of 107.

100 is a rectangular metallic bar supported by screws 101 passing into its ends through the frame 76. This bar passes through the lugs 99 99 of the paper-carriage, so as to permit them to slide upon it. Upon the top 100 of these lugs is fastened the ratchet-bar 96. The ink-ribbon 79 is fastened to threaded nuts 79 $\frac{1}{2}$, and is covered on its lower surface with printing-ink. Through these nuts pass screws 151 151, which have bearings in the 105 socket-sleeves 152 152, which are fastened at one side to the lugs 99 99. The paper to be printed upon is under the ink-ribbon and its sides pass into slots prepared therefor on the inner sides of the lugs 99.

82 is a bar fastened at a right angle to the armature 73. At the rear end of 82 is pivoted the pawl 77, which engages with the ratchet-wheel 78, which is secured to the stub-shaft 78 $\frac{1}{2}$. At the front end of 78 $\frac{1}{2}$ is secured a 115 spoke printing-wheel, 81, which acts upon the type 129. 78 $\frac{1}{2}$ is journaled in the frame 76, as shown in Fig. 4. On the front end of 82 is pivoted a link-arm, 88, and at the lower end of 88 it is pivoted to a similar arm, 88 $\frac{1}{2}$, which 120 is sleeved upon the shaft 78 $\frac{1}{2}$, and at the rear of this sleeve 88 $\frac{1}{2}$ project lugs, to which the spring-pawl 95 is pivoted, which engages with the ratchet-teeth of the bar 96, which bar forms a part of the paper-carriage. At the 125 other end of 88 $\frac{1}{2}$ is pivoted a spring-pawl, 89, which acts upon the ring ratchet-wheel 90 to disengage the pawl 35 and permit the type-wheel to return to its normal position.

91 is an arm projecting from the framework 76, as shown in Figs. 5 and 6. The inner or front end of the same is wedge-shaped to engage with a similar projection on the spring-pawl 89, for the purpose of disengag-

ing the pawl 89 from the ring ratchet-wheel 90 on its return motion, as shown in Fig. 5. On armature 73 is a vertical right-angled projection for the purpose of disengaging pawl 33; also, from 73 projects a similar arm, 61, which is so constructed as to be brought to the left of the type-wheel 30 $\frac{1}{2}$, and then bent at a right angle in an upward direction to disengage the pawl 29.

10 On the paper-carriage, at the rear of the right-hand lug 99, (shown in Fig. 6,) is secured a wedge-shaped piece, 106, to engage with the lug 114, attached to the stop-arm 102, as shown in the same figure, which moves the 15 arm 102 to the left, as shown in Fig. 3, a slight distance. Journaled into the lug 99 is the shaft 112. On this at each end are secured the spur-wheels 110, and also is journaled the lever 135, and at one end of 112 is pivoted a 20 spring-pawl, 136, to engage with one of the teeth on the spur-wheels 110. Attached to the other end of 135 is a light spring, 137, which is secured to the lug 99, for the purpose of keeping the lever 135 in a horizontal position and the spring-pawl 136 in contact with 25 one of the spurs of wheel 110. At the end of the lever 135 and in the rear of the pawl 136 is secured a wedge-shaped piece, 142, engaging with a similar piece, 152, which is secured 30 to the frame 76.

159 is a spring-stop secured to the lower end of one of the lugs 99 for the purpose of restraining the spur-wheel 110 from a backward motion.

35 Having described my mechanism, I now proceed to show how it is operated so as to utilize my invention.

When a positive unit-pulsation of electricity passes from a main battery through the 40 main-line wire 1, and by way of the main binding-posts 2, the coils of the neutral relay 4, the negative and positive magnets 8 and 10 of the polarized relay, out again toward the next station, such pulsation of electricity in 45 charging the neutral relay 4 attracts its armature 14 until, overcoming the resistance of the spiral spring 15, its platinum point 16 strikes the insulated adjustable set-screw 17, which is also platinum-tipped. This closes a local 50 circuit through the local wire 18 into one coil of the local magnets 19 19, and from this coil to the other by the connecting-wire, from the latter coil by wire 18, insulated set-screw 58, and (as the polarized armature 55 is in contact during this operation) through the pivot-screw 57, wire 61, local battery 23, and wire 18 to the local binding-post 25, thence to the pivot set-screw 27, thence through the armature 14 to complete the local circuit, which 55 60 has charged the magnets 19 19.

This electrical action attracts the armature 28, Fig. 3, bringing pawl 29 against one of the forty-eight ratchet-teeth of the wheel 30, and moves it right one tooth, where it is held by the 65 pawl 33. As pawl 31 is also attached to the same armature, its hooked end is carried over one of the eight teeth of the ratchet-wheel 32 $\frac{1}{2}$.

Now, as soon as the electrical connection is broken by the main-line currents through the neutral relay 4 and the retracting of its armature 14 by spring 15, then the retracting-spring 34 draws the local armature 28 back to its normal position, and as its lower pawl, 31, is hooked over a tooth of wheel 32 $\frac{1}{2}$ the latter is drawn left one tooth, (which is equal to four teeth of the wheel 30,) where it is held by the spring-pawl 35, pivoted to the wheel 30. As stated above, the wheel 30 has forty-eight teeth, and corresponding to these the wheel 30 $\frac{1}{2}$ has on its periphery two blank spaces and 80 forty-six types for printing letters, figures, and characters.

The code of characters, letters, and figures used by me is shown below, and their order of succession upon the wheel is indicated by 85 the figures at their left; and the dots and dashes at their right show what electrical pulsations are employed to make them.

Code of single and double unit-pulsations of positive electricity.

* The dots in the upper part of the spaces represent pulsations of positive, those in the lower pulsations of negative, polarity.

When the wheel is in normal position, the blank space 48 is directly below the center of the wheel 30, E is next toward the right, as the wheel is viewed in Fig. 3 of the drawings, 5 I second toward the right, and so on; hence the above partial revolution of the wheels 30 and 30 $\frac{1}{2}$ —that is, by a distance equal to one tooth of the former—brings the letter E directly below the center of the wheels, where 10 it can be impressed upon the ink-ribbon and paper below it by means to be fully described hereinafter.

To make "I," two pulsations like that above mentioned must be sent through the wire, and 15 "I" will then be below the center of 30 and 30 $\frac{1}{2}$, ready for printing. Now suppose the circuit-wheel to again be in its normal position. (How it is to be brought back into such position will be shown further on.) If a positive 20 current of a longer duration than the unit-pulsation above be sent from the transmitting main battery through wire 1 and parts inclusive, the first operation of this current, considered as a unit-pulsation, would be to advance the circuit-wheel one tooth; but if the 25 circuit is continued closed for another unit of time, then the upper end of armature 14, by striking against the right side of the local governing-escapement 39, imparts a momentum to 39 and carries its lever left until its platinum point 63 comes into electrical contact with the platinum point of the adjustable set-screw passing through the post 42 $\frac{1}{2}$, which is secured to a non-conducting base of 30 hard rubber, 66, attached to the top of post 40. Above operation will follow only when an electrical contact of longer duration than a single unit-pulsation occurs, because single unit-pulsations cause the lever 39 to vibrate 35 so rapidly that no electrical contact can be made between platinum point 63 and the set-screw which passes through the post 42 $\frac{1}{2}$. This closes a local electrical circuit as follows: through wire 41 directly into one of the 40 coils of the local magnets 42, and thence into the companion coil, thence by wire 41, connected at the metallic connection 67 $\frac{1}{2}$ with the local battery 47, and thence to the pivot-point of the escapement, and through its lever to the contact-point. This local circuit, by the armature 49, has brought the lever 45, which is pivoted to the lug 132 of the frame 75, upward until its spring-pawl 51, pivoted to the lever 50, comes in contact with one of the four pins 53. Now, as in 50 its normal position this pawl is outside or below the circle whose circumference passes through these four pins, the initial up movement of lever 50 has, by its arm 54, lifted the pawl 51 from contact with a tooth of the ratchet-wheel 32 $\frac{1}{2}$, where it has been carried by the unit or initial movement of this circuit, and then the further up movement of the pawl 52 against pin 53 revolves both the 55 small wheels 32 and 32 $\frac{1}{2}$ and also the wheels 30 and 30 $\frac{1}{2}$ forward a distance equal to eleven teeth on the wheel 30, which would bring the

twelfth character below the spoke printing-wheel. If another long pulsation were imparted, the wheel would be revolved twenty-four teeth, or to the letter M. So the operations of the armature 49, which move the wheels 32 and 32 $\frac{1}{2}$ forward, do so from whatever position a previous unit-pulsation has left them in. As soon as this circuit is broken then the retracting-spring 52 draws the lever 50 and the spring-pawl 51, and consequently the armature 49, back to their normal position. Now, if, instead of a long positive electrical pulsation accomplishing this 80 last movement of the wheels 30 and 30 $\frac{1}{2}$, a negative unit-pulsation of electricity be sent from the main battery, the same result will be accomplished, as I will now proceed to explain. 85

The action of a negative current through the wires and posts from 1 at the extreme right of Fig. 1 to 8 of the same figure is the same as before described in the positive current, and it makes no difference how many 90 positive pulsations had been sent. The polarized armature 55, which is pivoted to the permanent magnet 56 at 57, would remain resting against the insulated set-screw 58, but the neutral relay 4 would respond to 95 not only these positive but also to negative pulsations; but now a negative pulsation draws the lower end of armature 55 right, (and this negative current, in passing through the positive magnet 10, helps the movement 100 by repelling the armature until it rests against the insulated set-screw 59.) Then a local current passes through wire 60 directly into the magnets 42, and thence by the electrical connection 67 to the wire 18, and 105 through this to set-screw 17 and (as the main circuit closes on the neutral relay by either polarity) to armature 14 at the pivot-point 27, thence to wire 18 and to the binding-post 25, thence to local battery 23, wire 61, pivot-screw 57, back to the polarized armature 55. This negative unit-pulsation therefore revolves the wheel 30 one-fourth its circumference if this wheel was in normal position at the start; but if a positive pulsation has left 110 it in any other than normal position, then the negative current completes a quarter-revolution. 115

Whenever neither positive nor negative currents are passing over the main line, then 120 armature 14 of the neutral relay is drawn back by spring 15 against the insulated set-screw 62, and the momentum thus imparted to the governing lever-escapement 39 throws it into the position shown in Fig. 1, with its platinum point 63 against the platinum-tipped set-screw in post 64, which is screwed to the rubber plate 66, and now a local circuit is formed through the wire 67 into and through the coils of magnets 68, thence by wire to the 125 metallic connection 67 $\frac{1}{2}$, thence by wire 41 to the local battery 47, thence to the pivot-point of 39. This charges the magnets 68 68. These attract armature 73, Fig. 5, pivoted at

74 to the frame 75, and its left end is thus elevated, and its hooked pawl 77, engaging a ratchet-tooth, (see section view, Fig. 5,) revolves this ratchet-wheel 78 one tooth. This brings one 5 of the eight arms of the spoke wheel 81, Fig. 2, down upon the upper part of whatever type is to be printed. This type is forced down upon the ink-ribbon 79, and an imprint is thus made upon the paper 80. As soon as one of 10 the arms of 81 passes off the type its spring returns it to its normal position. Then the light flat spring 83, fastened to the wheel 32½ and to the shaft 127, throws the ratchet-wheels 32 and 32½ back, right, until the short pin 85 15 strikes the hooked portion of the rigid arm 84. This flat spring 83 has been tightened by the previous left movement of the wheels 32 and 32½. At the same time the mainspring 86 of the wheel 30 that has been tightened 20 the right movement of this wheel, throws it left until its pin 87 strikes against the pawl 31, which cannot be depressed, because the arm 54 holds it up. Referring now to the section view, Figs. 3 and 5, by lifting the armature 73 and the arm 61, the pawl 88, by the arm 89, to which it is pivoted, draws the hooked end of pawl 89 down against a tooth of the ring ratchet-wheel 90. As the spring-pawl 89 25 descends, through the action of the lever 88½ and its connections with the armature 73, the wedge-shaped projection 91 is so constructed, as shown in Fig. 5 of the drawings, that on the downward motion of the pawl 89 it will be forced into contact with one of the 30 teeth of the ratchet-wheel 90, thereby moving it in the direction of the arrow, as shown in Fig. 4, so as to bring the pin 93 (shown in Fig. 3) in contact with the projecting arm of the spring-pawl 33, thereby disengaging the same 35 40 from the wheel 32; and it will be seen in Fig. 3 that the upward movement of the right-angled piece of the armature 73 will also disengage the spring-pawl 33. Attached to 73 is the arm 61, similar to the right-angled piece 45 above mentioned, and in such a relation to the other parts of the mechanism for disengaging the pawl 33 as to be brought up and in contact with pawl 29, thereby disengaging it at the same time from the ratchet-wheel 30, and then 50 by the action of the flat spring 86, Fig. 4, on the type-wheel 30½ it is brought back into normal position. This operation is repeated until a line is finished across the paper on which the message is being printed. The 55 lifting of pawl 77 by the armature 73 carries the lower pawl, 95, (which is attached to the same sleeve that carries pawl 88,) left one tooth of the letter-feed ratchet 96, as shown in sectional view, Fig. 5; but in Fig. 3 it is 60 carried right one tooth, so that its pawl 89 engages with a tooth, so that when the contact with armature 14 of the governing-escapement 39 breaks the electrical connection between the platinum points 63 by the forward 65 movement of armature 14 (produced by a main-line current) then the wheels are again in their normal position, as shown above, and

all of the pawls by their respective springs are returned to their normal positions, and then the retracting-spring 143, Fig. 3, throws 70 the armature 73 back to its normal position and pawl 77 drops below another tooth. This left movement of the letter-feed ratchet carries the entire paper-carriage along the supporting-bar 100. The horizontal section of 75 stop-arm 102, Fig. 3, drops over the teeth successively of the feed-ratchet, to prevent the weight 103, suspended by a cord over pulley 104, attached to the frame 76, from pulling 80 the paper-carriage back.

Whenever the paper has been carried left to within ten teeth of its end, then a projection, 106, on one of the lugs 99 strikes the down projection 114 of stop-arm 102, thus moving said stop-arm left one-eighth of an 85 inch, and whenever the word then being printed (which is the last word on a line) is finished the pin 105 on wheel 30 strikes the stop-arm 102 and pushes it left another one-eighth of an inch. The projection 108 on the 90 top of 102 is thus brought over the lug 109 upon the pawl 31. Then when the magnets 42 act on armature 49, (which they are made to do at the end of this word,) 49 lifts the lever 50, and with it 54, which lifts pawl 31, and 95 thus lug 109 is forced upward against projection 108, arm 102 is raised above ratchet-bar 96, and the weight 103 is permitted to draw 100 the paper-carriage back to its original position. When the paper-carriage reaches its extreme right-hand position, the beveled lug 142 will travel up and on the surface of a 105 similar wedge-shaped lug, 152, and thereby advance the spring-pawl 136, which is engaged with a tooth of the spur-wheel 110, and thus 110 move the spur-wheels and paper forward one line. This tripping of stop-arm 102 to allow the weight 103 to carry the paper-carriage right and to revolve the wheels 110 110 is accomplished also by four negative pulsations through the main line, or by four positive dash pulsations. In either case the wheel 115 115 has been revolved its entire circumference, and then the pin 87 of this wheel, normally checking the back movement of the wheel by 120 striking the pawl 31, will, when revolved the other way, come up under the pawl 31 and lift it. Meantime the pin 113 (which is properly located on wheel 30 to accomplish such 125 purpose as the following) has struck against arm 102 and moved it toward the left one-fourth of an inch; hence when pawl 31 is lifted by 87 arm 102 is also lifted from bar 96, allowing the paper-carriage to be drawn back to its original position.

The purpose of having the escapement allow one or more teeth to escape at a time is, that each of the forty-six characters on the type-wheel may be brought into position for printing by using the least number of electrical pulsations possible, thus avoiding the necessity of sending a separate pulsation for each tooth of said wheel.

I will now describe more in detail the op-

eration of bringing the letters and characters on wheel 30½ into position for printing. By referring to the codes, the order of succession of the letters and characters therein on the wheel 5 30½, and the normal position of said wheel, all shown above, the explanation following will be intelligible.

The letters E, I, S, O, and C in both codes are brought into position for printing by 10 transmitting, respectively, one, two, three, four, and five single unit-pulsations of positive polarity, which advance wheel 30 toward the right one to five teeth respectively, wheel 30½ of course moving with it.

15 The letter A is brought into position for printing in the following manner: A single unit-pulsation of positive polarity being transmitted, wheel 30 advances one tooth, wheel 32 turning with it. The circuit being 20 then broken, spring 34 retracts armature 28, and with it pawl 31, which turns wheel 32 left a space corresponding to six teeth of wheel 30; but wheel 32 having turned toward the right with wheel 30 any point in the 25 former—as pin 53, for example—will be back of its original position a space corresponding to five teeth of wheel 30. Now sending a double unit-pulsation of positive polarity, its first half will produce a current through magnets 30 19, armature 28 will be drawn toward the right, and wheel 30 will be thus turned forward one tooth. Pin 53 will then be back of its original position a space corresponding to four teeth of wheel 30, the pulsation continuing through the second half of its duration, the left platinum point 63 of lever 39 is brought into contact with the set-screw passing through post 42½, and thus a current of electricity is sent through magnets 42. 35 These attract armature 49, which, moving upward, carries with it lever 50, arm 54, and pawl 51. Arm 54 lifts pawl 31 from contact with the teeth of wheel 32, and pawl 51 moves up to pin 53 and carries it upward till the 40 pawl passes out of the circle in which the pin moves, having thus carried the pin through a space corresponding to four teeth of wheel 30; hence A, being on the sixth space of wheel 30, will now be in position for printing. 45 50 How the act of printing is accomplished has been fully explained above.

The letter F is brought into position for printing by repeating the operation for the letter A and then imparting, in addition, a 55 single unit-pulsation of positive polarity, and the letters R, H, G, and N are produced in like manner—that is, by adding such a pulsation after each letter to make the next.

Corresponding to the twelfth tooth on wheel 60 30 there is a blank space instead of a character. To bring this over the printing-point a double unit-pulsation of positive polarity is transmitted. The initial impulse of this sends a current through magnets 19. Thus armature 28 is attracted and wheel 30 is advanced one tooth and pin 53 a corresponding distance; but the final impulse causes a current to pass

through magnets 42, as shown above, armature 49 is drawn upward, lifting lever 50, arm 54, and pawl 51, thus carrying pin 53 through 70 a distance corresponding to eleven teeth of wheel 30.

The letters T, D, B, L, and the apostrophe (') are brought into position for printing by repeating the above operation and then adding one, two, three, four, and five single unit-pulsations of positive polarity, respectively. 75

The method of reaching the characters K to the colon (:) is obvious. The letter M is opposite to the twenty-fourth tooth on wheel 80 30. It is brought into position for printing by repeating twice the operation for producing the blank space. The period, (.) Y, U, V, and W are brought into position for printing by adding, respectively, one, two, three, 85 four, and five single unit-pulsations of positive polarity to the pulsations required to produce the letter M.

The letter X is brought into position for printing by repeating the operation for the 90 letter M and adding thereto the operation required for the letter A.

The letter Z and the characters and, (&,), parenthesis, ( ) and (,), and dash (—) are brought into position for printing by adding, 95 respectively, one, two, three, four, and five single unit-pulsations of positive polarity to the operation required for the letter X.

The method of producing the remaining characters is now too obvious to require further explanation. 100

The method of producing the letters and characters by the code of single unit-pulsations of positive or negative polarity is the same as that above described, the pulsation 105 of negative polarity being substituted for the double unit-pulsation of positive polarity.

In utilizing my invention I do not want to be restricted to the employment of the particular telegraphic vocabulary set forth hereinbefore, nor do I want to be restricted to the use of a wheel with exactly forty-eight teeth. Other vocabularies may be formed and wheels with teeth suitable for the use of such vocabularies to utilize all the essential elements of my invention. Neither do I wish to be restricted to the eight teeth at equal distances apart on the smaller ratchet-wheel, nor to the four pins thereon, as by changing these parts any combination may be adopted. 115 120

Having thus described my invention, what I claim as new, and desire to secure by Letters Patent, is—

1. In a telegraphic printing-machine, the adjustment-post 40, in combination with the 125 adjustment-posts 42½ and 64, the lever-escapement 39, the set-screws 17 and 62, and the retracting-spring 15, substantially as and for the purposes specified.

2. In a telegraphic printing-machine, the 130 wire 67, in combination with the adjustment-post 64, the magnets 68, the electrical connection 67½, the local battery 47, the wire 41, the lever-escapement 39, the armature 14, the

spring 15, and the insulated set-screw 62, substantially as and for the purposes specified.

3. In a telegraphic printing-machine, the wire 18, in combination with the set-screw 17, 5 the magnets 19, the local battery 23, the binding-post 25, the armature 14, the wire 18, the set-screw 58, the armature 55, the wire 61, the positive magnet 10 of the polarized relay, and the neutral relay 4, substantially as and for 10 the purposes specified.

4. In a telegraphic printing-machine, the wire 41, in combination with the lever-escape- 15 ment 39, the local battery 47, the magnets 42, the adjustment-post 42½, the wire 60, the insulated adjustment-post 59, the armature 55, 20 the wire 61, the local battery 23, the wire 18, the binding-post 25, the armature 14, the negative magnet 8 of the polarized relay, and the neutral relay 4, substantially as and for the purposes specified.

5. In a telegraphic printing-machine, the ratchet-wheel 30, slotted at the point 92 and having forty-eight teeth equally distant from each other, which engage with the spring-pawls 29 and 33, in combination with the pawls 35 and the wheel 30½, bearing on its periphery forty-six type-characters for printing, said wheels revolving on the shaft 127, fixed in the vertical frame 75, substantially as and for the 30 purposes specified.

6. In a telegraphic printing-machine, the type-wheel 30½, in combination with the coiled spring 86, attached to the shaft 127, the ring ratchet-wheel 90, and the ratchet-wheel 30, substantially as and for the purposes specified.

7. In a telegraphic printing-machine, the ring ratchet-wheel 90, having forty-eight teeth corresponding to those of wheel 30 and which 40 engage with the pawl 89, in combination with the three slotted lugs 158 and the wheel 30½, substantially as and for the purposes specified.

8. In a telegraphic printing-machine, the ratchet-wheel 32½, having eight teeth, in combination with the spring 83, attached to the shaft 127, and with the ratchet-wheel 32, having eight corresponding teeth which engage with the pawl 35, said wheels revolving on 50 shaft 127, substantially as and for the purposes specified.

9. In a telegraphic printing-machine, the combination of armature 28, magnet 19, pawl 31, spring 34, and the ratchet-wheel 30, engaging 55 with the pawl 29, which revolves said wheel one tooth at a time, said wheel bearing on its side the pawl 35, engaging with ratchet-wheel 32, connected with ratchet-wheel 32½, which revolves wheel 30 eight teeth at a time, 60 as hereinbefore shown.

10. In a telegraphic printing-machine, the lever 50, in combination with the armature 49, the lug 132, extending from the frame 75, the spring-pawl 51, engaging with the pin 53 on 65 wheel 32½, and the retracting-spring 52, substantially as and for the purposes specified.

11. In a telegraphic printing-machine, the

stop-arm 102, normally resting across the ratchet-bar 96, having a depending branch, 70 114, the arm continuing upward as a bent lever around the wheel 32 and above the projection 109 on the pawl 31, bent near its upper end at right angles twice and terminating in a wedge-shaped projection extending horizontally over pawl 31, said arm 102 being 75 slotted, and in combination with the frame 75 at the point 148, substantially as and for the purposes specified.

12. In a telegraphic printing-machine, the armature 73, pivoted at the point 74 to the 80 frame 75, and attracted by the magnets 68 68 when a local current of electricity is passing through them, in combination with the cross-bar 82, pivoted at one end to the hooked spring-pawl 77, which engages with the 85 ratchet-wheel 78, and at the other end to the link-bar 88, substantially as and for the purposes specified.

13. In a telegraphic printing-machine, the stub-shaft 78½, having bearings in the frame 90 75, in combination with the ratchet-wheel 78 and the spoke-wheel 81, which impinges upon the type-bearing plates 129, substantially as and for the purposes specified.

14. In a telegraphic printing-machine, the 95 sleeved lever 88½ upon the stub-shaft 78½, in combination with the link-bar 88, and the hooked pawl 89, engaging with the teeth of the wheel 90, and having on it a wedge-shaped projection corresponding to and in contact 100 with the like projection on the bar 91, fastened to the horizontal frame 76, substantially as and for the purposes specified.

15. In a telegraphic printing-machine, the lugs 99, slotted on their inner faces to receive 105 the sides of the sheet of paper to be printed on and apertured to pass over the bar 100, supported by the screws 101, passing into it through the frame 76, in combination with the ratchet-bar 96 and the socket-sleeves 152, 110 which receive the screws 151, substantially as and for the purposes specified.

16. In a telegraphic printing-machine, substantially as described, the combination of the magnet 42, armature 49, lever 50 and its vertical arm 54, pawl 31, arm 107 and its projection 108, arm 102, ratchet-bar 96, lugs 99, weight 103, pawl 95, and wheels 78, as and for the purposes stated.

17. In a telegraphic printing-machine, the 120 ratchet-wheel 78, in combination with the pawl 95 and the stub-shaft 78½, and engaging with the pawl 77, substantially as and for the purposes specified.

18. In a telegraphic printing machine, the 125 combination of the armature 73, pivoted to the frame 75 below the magnets 68 68, the lever 82, resting on said armature, the pawl 77, pivoted to said lever and engaging with ratchet-wheel 78, pivoted on stub-shaft 88½, 130 the pawl 95, pivoted on the sleeve 78½ of wheel 78 and engaging with the ratchet-bar 96, the stub-shaft 88½, pivoted to link-arm 88 and to pawl 89, the ratchet-ring 90, loosely secured

by screws passing through its slots 158 to wheel 30 $\frac{1}{2}$, and the pin 93, rigidly secured to said wheel and passing through slot 92 in wheel 30 directly beneath the upper arm of pawl 35, 5 substantially as and for the purposes specified.

19. In a telegraphic printing-machine, the stub-shaft 88 $\frac{1}{2}$, in combination with the link-arm 88, the ratchet-wheel 78, and the spring-pawl 89, which engages with the ratchet-wheel 90, substantially as and for the purposes specified. 10

20. In a telegraphic printing-machine, the shaft 112, in combination with the lugs 99, the spur-wheels 110, the weight 103, and the 15 pivoted lever 135, substantially as and for the purposes specified.

21. In a telegraphic printing-machine, the pivoted lever 135, bearing the wedge-shaped piece 142 at one of its ends, which piece slides 20 up on a corresponding wedge-shaped piece, 154, fastened to the frame 76, in combination at above end with the spring-pawl 136, engaging with the teeth of one of the spur-wheels 110, and at the other end in combination with 25 the spiral spring 137, fastened to the lug 99, substantially as and for the purpose specified.

22. In a telegraphic printing-machine, the spring 159, secured at one end to the bottom of that lug 99 which is nearest to the weight 103, in combination with a small lug notched 30 in its upper face to receive a tooth of wheel 110, said notch being made shallow and spring elastic enough to permit the said wheel to re-volve, as shown.

23. In the paper-carriage of a telegraphic printing-machine, the lever 135, pivoted on the shaft 112 near one of the lugs 99, carrying fixed to it at one end the spring-pawl 136 in contact with a tooth of wheel 110, and carrying the beveled piece 142 at this end to slide 40 up on the beveled end of arm 154, fixed rigidly to the frame 76, thus partly revolving the wheel 110 on the return of the paper-carriage after the printing of a line and automatically moving the paper forward for the printing of 45 a new line, substantially as shown.

ZEROY P. HOTCHKISS.
